Primary Examiner — Bao-Yen T Nguyen*Assistant Examiner* — Loryn K. Leblanc(74) *Attorney, Agent, or Firm* — Jose Cherson Weissbrot(57) **CLAIM**

The ornamental design for an eyewear retainer, as shown and described.

DESCRIPTION

FIG. 1 is a front perspective view of an eyewear retainer, showing my new design;

FIG. 2 is a rear perspective view thereof;

FIG. 3 is a front elevation view thereof;

FIG. 4 is a rear elevation view thereof;

FIG. 5 is a left side view, the right side view being a mirror image of FIG. 5;

FIG. 6 is a top plan view thereof; and,

FIG. 7 is a bottom plan view thereof.

The broken lines in the figures depict portions of the eyewear retainer, that form no part of the claimed design. The article is shown with a symbolic break in its length. The appearance of any portion of the article between the break lines forms no part of the claimed design.
